UNITED STATES PATENT OFFICE

2,371,791

MANIFOLD STATIONERY

Thurston V. Berggren, Chicago, Ill., assignor to
United Autographic Register Co., a corporation
of Illinois

Application March 11, 1943, Serial No. 478,751

4 Claims. (Cl. 270—52)

This invention relates to manifold stationery, and more particularly to printed continuous-form stationery provided with interleaved carbon wherein the superposed strips are secured together.

The primary object of the invention is to provide an improved method for obtaining proper registration between the record strips and the transfer or carbon strips wherein the strips of carbon in the final product are narrower than the record strips. This is accomplished by providing a detachable guiding strip on each of the strips to furnish a guiding edge to enable the stationery to be guided or jogged into proper registration. After the registered strips are secured together, the guiding strips may be readily detached.

Another object of the invention is to provide a convenient way for forming cut-out areas in the transfer strip when it is desired that certain notations made on the top strip will not be transferred through to all of the underlying record strips.

Still another object of the invention is to provide a convenient way for positioning narrow transfer strips between the rows of marginally punched holes in stationery of the type used in teletype machines, and the like.

The invention is illustrated in preferred embodiments in the accompanying drawing, in which—

Figure 1 is a broken plan view of stationery embodying the invention before the guiding strips have been detached; and Figure 2, a fragmentary view showing how the guiding strips may be detached after the stationery has been assembled.

In the embodiment illustrated, record strips 3 may be printed with suitable notations and, if desired, provided with lines of marginal perforations 4. The record forms are scored, as indicated at 5, outside of the line of punch holes to provide a detachable guiding strip 6.

Strips of transfer material, such as one-time carbon 7, may be of narrower width than the record strips so that it is necessary to provide a detachable guiding strip 8 which is connected to the main body of the carbon along a line of scoring 9. After the record strips and the transfer strips have been brought into proper interleaved relation, they may be jogged into registration along the free edges 10 of the guiding strips. The stationery is then secured together by fastening means 11 which may be in the form of staples, sewing, or the like, provided at lines of weakening 12 provided between sets of forms.

In some cases, it is desirable to have cut-out portions 13 in the transfer strips so that all of the notations will not be imprinted on the underlying forms. Such areas 14 may be provided by 5 outlining them with the line of scoring 9 before assembly.

After the stationery has been assembled and the strips secured together, the guiding strips on both the record forms and transfer strips may be 10 readily detached, as indicated in Figure 2, and discarded.

The foregoing detailed description has been given for clearness of understanding only, and no 15 unnecessary limitations should be understood therefrom for some modifications will be obvious to those skilled in the art.

I claim:

1. The method of manufacturing manifold stationery, which comprises: printing record strips 20 and scoring one marginal portion to provide a detachable guiding strip; scoring a transfer strip to form a detachable guiding strip of a width greater than that of the first mentioned guiding strip; interleaving the transfer strip with the record strips and using the free edges of the guiding strips as guides to bring the stationery into proper registration; securing the main bodies of the superposed strips together; and detaching the guiding strips.

2. The method of manufacturing manifold stationery, which comprises: printing and punching record strips and scoring one marginal edge portion to provide a detachable guiding strip; scoring a transfer strip, of narrower width than the record strips, to form a detachable guiding strip of a width greater than that of the first mentioned guiding strip; interleaving the transfer strip with the record strips and using the free edges of the guiding strips to bring the stationery into proper registration; securing the main bodies of the superposed strips together; and detaching the guiding strips.

3. The method of manufacturing manifold stationery, which comprises: printing record strips and punching therein marginal lines of perforations; scoring one marginal portion outside of the lines of perforations to provide a detachable guiding strip; scoring a transfer strip 45 to form a wider detachable guiding strip for the main body of the transfer strip, said main body having a width less than the distance between the lines of punching in the record strips; interleaving the transfer strip with the record strips 50 and using the free edges of the guiding strips

to bring the assembly into proper registration; securing the main bodies of the superposed strips together; and detaching the guiding strips so as to leave the punched marginal portion of the record strips clear of the remaining interleaved transfer material.

4. The method of manufacturing manifold stationery, which comprises: printing record strips and scoring one marginal portion to provide a separate detachable guiding strip; scoring a transfer strip along one margin to form a de-

5
10
tachable guiding strip which includes certain desired adjacent areas of the main body of the transfer strip; interleaving the transfer strip with the record strips and using the free edges of the guiding strips to bring the stationary into proper registration; securing the main bodies of the superposed strips together; and detaching the guiding strips and the area outlined by the scoring in the transfer strip.

THURSTON V. BERGGREN.
